SHOWCASE

Walter A. Lapham, Chicago, Ill., assignor to E. J.
Brach & Sons, Chicago, Ill., a corporation of Illinois

Application November 21, 1947, Serial No. 142,711

Term of patent 14 years

(CL. D80—11)

To all whom it may concern:

Be it known that I, Walter A. Lapham, a citizen of the United States, residing at Chicago, in the county of Cook and State of Illinois, have invented, a new, original, and ornamental Design for a Showcase, of which the following is a specification, reference being had to the accompanying drawing, forming a part thereof.

In the drawing:

Fig. 1 is a perspective view of a showcase embodying the design; and

Fig. 2 is a front elevational view thereof.

I claim:

The ornamental design for a showcase, substantially as shown.

WALTER A. LAPHAM.
